UNITED STATES PATENT OFFICE.

CHARLES H. FIELD, OF PROVIDENCE, RHODE ISLAND.

ENGRAVING MACHINE.

Application filed June 23, 1921. Serial No. 479,903.

To all whom it may concern:

Be it known that I, CHARLES H. FIELD, a citizen of the United States, residing at Providence, in the county of Providence and State of Rhode Island, have invented 5 certain new and useful Improvements in Engraving Machines, of which the following is a specification.

This invention relates to improvements 10 in engraving machines more particularly of the planer type; and has for its object to provide a machine of this character having means for automatically arresting the action of the tool upon the work when the 15 work is finished and to automatically discharge the work when finished and position fresh work therein.

A further object of the invention is to 20 provide means for producing lateral vibrations of the tool while operating longitudinally upon the surface of the work.

A still further object of this invention is 25 to provide a series of patterns for controlling the lateral vibrations of the tool while operating upon the work.

My invention further consists in the provision of a plurality of means for automatically positioning the various patterns to control the vibrations of the tool while acting 30 upon the face of the work.

The invention further consists in the provision of means for raising the tool from the work at predetermined intervals during the relative longitudinal movement of 35 the work; also the provision of means for controlling the action of the tool upon the face of the work so as to leave blank spaces of the desired width on the work either for the length of the work or for any portion 40 thereof.

With these and other objects in view, the invention consists of certain novel features of construction, as will be more fully described, and particularly pointed out in the 45 appended claims.

In the accompanying drawings:—

Figure 1 is a side elevation of my improved engraving machine.

Figure 2 is a plan view of the machine.

Figure 3 is a perspective view showing in 50 detail the tool head as supported on a pair of resilient arms.

Figure 4 is a partial plan view of the machine with the magazines removed to 55 better show the operating mechanism below.

Figure 5 is a sectional elevation on line

5—5 of Figure 2, looking from the front of the machine.

Figure 6 is a vertical section on line 6—6 of Figure 2 looking from the rear of the 60 machine.

Figure 7 is a plan view of a portion of the bed, showing the bar for releasing the clutch which drives the work carriage reciprocating mechanism. 65

Figure 8 is a perspective view illustrating the mechanism for tripping and releasing the carriage stopping bar.

Figure 9 is a perspective view showing the protruding end of the carriage stopping bar 70 in position to engage the latch and withdraw the clutch to arrest the action of the work carriage; also showing the cam for repositioning the clutch to again start the carriage after fresh work has been positioned thereon. 75

Figure 10 shows the mechanism for repositioning the carriage operating stop bar which occurs just before the clutch has been drawn in. 80

Figure 11 is a perspective view showing the means controlled by the carriage for lifting the tool-head at the end of a working stroke, also showing the means for dropping the tool-head thus bringing the 85 tools into contact with the work at the beginning of a working stroke.

Figure 12 shows the mandrels as positioned and locked into tubular work.

Figure 13 shows the mandrels as having 90 been partially withdrawn from the tubular work.

Figure 14 shows the mandrels as having been fully withdrawn from the work also indicating portions of the magazines for 95 positioning fresh work to be mounted upon the mandrels; also showing the mechanism for operating the tailstock or end support for the free ends of the mandrels.

Figure 15 is a perspective view illustrating the mechanism by which the magazines may be moved to position the work to receive the mandrels and subsequently raise the magazines into the position best illustrated in Figure 5. 100

Figure 16 shows an enlarged side elevation of the neck portion of the magazine illustrating the end stop for the work and the spring pressed fingers for holding the work while in the neck of the magazine. 110

Figure 17 is an enlarged view of the free end of the mandrel showing the pivoted

fingers adapted to expand and grip the internal surface of the work to hold it firmly so that it is positively driven by the rotating motion of the mandrel.

5 Figure 18 is an end view of the mandrel showing the expanding fingers.

10 Figure 19 shows a set of equalizing levers which are adapted to be mounted in the tool-head, the same being adapted to compensate for unevenesses in the surfaces of the various pieces of work operated upon by the tools; a single compensating lever being illustrated in dotted lines in the head shown in Figure 5, for a pair of tools.

15 Figure 20 is a plan view showing a portion of the carriage on which is mounted a plurality of pattern bars for controlling the raising from or lowering of the tool onto the work during its longitudinal travel 20 thereafter.

25 Figure 21 is a vertical section on line 21—21 of Figure 20, showing the pattern bar for causing a vertical vibration of the tool as it passes along the surface of the work; also showing the cam for controlling the positioning of this pattern bar.

30 Figure 22 is a sectional elevation on line 22—22 of Figure 20, looking in the direction of the arrow and showing another pattern bar which is adapted to raise the tool from the work during a complete stroke if desired to leave a plain surface, or unfigured surface, and showing the cam for controlling the action of this bar.

35 Figure 23 is a side elevation of a portion of my machine illustrating the pattern roll also illustrating the pattern roll for producing lateral vibrations of the working tool; also showing the mechanism for operating 40 the roll automatically.

Figure 24 is a perspective view illustrating a portion of one of the cams for producing a rotating motion of the pattern roll.

45 Figure 25 is a perspective view showing the lock latch for releasably retaining the pattern roll in adjusted position.

50 Figure 26 is a perspective view showing a modified form of work-support which is adapted to hold the work which does not have to be rotated in order to present the surface which is desired to be finished.

55 Figure 27 illustrates one form of work having a flat surface which has been finished in my improved machine.

55 Figure 28 shows another or tubular form of work which has been acted upon or finished in my improved engraving machine.

60 My improved engraving machine is of the planer type and is more particularly adapted for operating upon tubular work such as pen and pencil cases and the like, which are mounted upon a carriage to move longitudinally and also to be rotated on centers upon the carriage to present different portions of the surface to be operated upon by

the engraving tool; also other work such as that having flat, oval, dome-shaped, or rounding surfaces or surfaces of other forms may be operated upon and on which surfaces the tool may produce lines which are straight and continuous, broken or interrupted, wavy or laterally deflected, or any other desired form of ornamentation may be produced which are capable of being formed by a combination of lateral and longitudinal movements of the tool upon the work.

70 My improved machine is also provided with means whereby the work to be ornamented may be automatically positioned in the machine and after all of the operations have been automatically performed thereon the work will be discharged from the machine and the cycle of operations successively repeated until the work in the feeding magazine has been exhausted; and the 75 following is a detailed description of one means by which these results may be accomplished:—

80 With reference to the drawings, 30 designates the bed of the machine on which the carriage 31 is mounted to reciprocate in ways 32, its motion being received from the crank 33 on the main drive shaft 173, see Figure 1, through the connecting bar 34, the 85 throw of this crank being adjustable by means of a screw 35 to regulate the length of the operating stroke of the work relative to the tool, and the carriage may be adjusted lengthways independently of the 90 stroke by means of a screw 36 to position the work relative to the tool.

95 The mechanism herein illustrated is more particularly adapted for operating upon work of a tubular form such as pen and pencil casings and the like and this work is mounted upon the carriage between the headstock 37 and the tailstock 38, see Figure 4.

100 Any convenient number of tubes may be 100 mounted between this head and tailstock but for convenience I have shown but two, one on either side of the machine.

105 In order to support these pieces of work in a practical way I have mounted mandrels 110 39 adapted to be moved in and out through this head stock 37 to pass through the tubes when positioned to receive such mandrels. These mandrels are all connected to a cross-head 40 see Figures 12, 13 and 14 and are 115 adapted to be drawn out by means of a cam 41 and forced into position to engage the work by a cam 42 both of which are mounted on a rotatable disk 49 to alternately engage the projection 43 on the slide bar 44 to 120 move it vertically and so transmit motion to the yoke and mandrels through connection 45, crank 46, arm 47 and bar 48 to move them to operative position.

125 When the cross-head is carried forward 130

the mandrels are inserted into the work and the latch 50 snaps over the back of the cross-head locking it and the mandrels in this forward position.

5 A clutch member 76^a forms a part of the mandrels so that when they are carried to their forward position this clutch engages a corresponding clutch portion on the hubs of the driving gears 77, presently described, so 10 as to rotate the mandrels and their different pieces of work in unison.

Before the yoke can now be withdrawn from this in or operating position its locking latch 50 must be withdrawn therefrom. To do this at the proper time I have provided a cam 50^a on disk 49, which is mounted with the other cams on cam shaft 175 which shaft is operated from the main drive shaft 173 through the differential gearing 174 whereby the cam 50^a rocks the arms 51^a and 52^a to withdraw the latch and releases the yoke 40 at the proper time.

It is found in practice desirable to support the free end of these mandrels while the work is being operated upon and it is also found of advantage to provide means in the mandrels for gripping the work to bind the same to the mandrels and cause it to always rotate therewith. To do this I have provided a tailstock 38 in which is mounted a tailstock center or support 51 see Figure 4, the outer end of which is recessed to receive and support the free end of the mandrels, which end of the mandrels is provided with 35 a pair of expanding, gripping jaws 52 pivoted at 53 in the slotted end of the mandrels, see Figures 17 and 18, between which jaws is mounted a central expanding pin 54 whose outer end extends beyond said jaws.

40 During the time that these mandrels are being forced into the work, their centers or supports 51 are withdrawn from operating position by the engagement of the cam 55, mounted on the disk 56, with the inclined surface 57 of the lever 58, which acts through the connection 59, long rock arm 60 pivoted at 61, connection 62, short rock arm 63, latch 64 and shaft 64^a, to hold these centering supports back against the tension 45 of their springs 65, and when this cam 55 moves out of contact with its lever 57, these centering members are released to move forward under influence of their springs 65, each to engage the end of its mandrel and 50 force inwardly the centering pin 54 to expand the jaws 52 causing them to grip and bind the work thereon; also serving to support the free end of the mandrels and the work during the period it is being operated 55 upon.

Over each piece of work I mount an engraving tool 67 all to work in unison in a tool-head 68; and in some cases where but two are used they are supported on a single 60 compensating rock bar 69 as illustrated in

dotted lines in Figure 5, while when a greater number are employed they may be supported on a series of compensating levers 70 illustrated in Figure 19 so as to equalize the pressure of the several tools upon the 70 surface of the work.

As this tool-head 68 must be capable of transmitting a vertical vibration or motion to the tools I have mounted the same upon a pair of resilient arms 71, see Figures 2 and 3, 75 the opposite ends of which are connected together by a bar 72 which is pivotally mounted on centers 73 and the tools are caused to produce a yielding pressure upon the work through action of the flat spring 74 which 80 is provided with an adjusting screw 75 by which the required pressure of the tool upon the work may be readily obtained.

When other than tubular work is operated upon such for instance as flat work 180 85 as illustrated in Figures 26 and 27, this work may be mounted in a chuck 76 or other convenient holder and moved transversely on the carriage during the longitudinal movement of the carriage beneath its tool by means of the screw 181 operated by the pawl 182, but when it is desired to operate upon tubular work such as pen and pencil casings and the like, this work must be rotated upon its carriage in order to present 90 its whole surface, or any required portion thereof, to the operating tool, and in order to accomplish this I mount a gear 77 on each of the mandrel supporting bearings and these gears are connected through the idlers 95 78 to engage the driver gear 79 which latter is mounted upon the shaft 80 to the rear end of which is fixed a ratchet gear 81 through which this shaft receives a step-by-step rotation motion to impart the same through 100 said gears to the work during the operation of the tool thereon.

105 In order to produce this step-by-step motion to the shaft I mount a bar 82 to slide transversely in the groove in the carriage 81, action being given to this bar by engagement of its protruding end 83, see Figure 7, with the relatively-fixed cam 84 on the bracket 85 whereby at the end of each operating stroke of the carriage this bar upon engaging this fixed cam 84 is moved inwardly endways and its latch or pawl 86 engages a tooth in the ratchet wheel 81 and so imparts to the same a step-by-step rotation. As will be seen this cam 84 may be adjusted 110 by the screw 87 on its bracket 85, so as to impart to the bar 82 sufficient motion to rotate the ratchet the desired number of teeth at each stroke, to produce the desired effect 115 of the tool upon the work.

120 This step-by-step rotating motion of the work continues until the same has, preferably, made a complete revolution when the trip pin 88 which is carried by the shaft 80 comes in contact with and depresses the 125

latch 89, which is pivotally connected to bar 90, to release this bar, which, under action of its compressed spring 91, now moves forward until the taller lip 89^a of the latch 5 brings up against plate 90^a, which movement causes the bar to extend into position to engage the rocker latch 92, see Figure 9, to swing the same as the carriage moves forward to the end of its inoperative stroke, to 10 move the lever 93 and cause it to withdraw the clutch 94 and arrest further motion of the carriage by disconnecting the main drive shaft 173 and its carriage driving crank 33 from the rotating pulley 95 which runs continuously. 15

The next operation, after the carriage has stopped, is to unlock and withdraw the mandrels 39 from the work in the manner above described, which withdrawing action releases the finished work permitting it to 20 drop by gravity from its working position, after which the magazines 96 in which the fresh work is stored, are each moved to locate a fresh tube in position to receive its 25 mandrel and after all of the mandrels have been again positioned and locked in the work the magazines are removed ready to start the machine into action.

The magazines best illustrated in Figures 30 5 and 15 may be formed in any suitable shape to support a multiplicity of tubes or pieces of work above their respective work supports, and in Figure 15 I have shown them as connected to a cross-bar 99 which 35 slides vertically in guides 100, the same being first moved to lower the magazines with their work into the proper position, by presenting the recessed portion 101 of the cam 102 to the vertical member 109, which, 40 through crank 110 and lever 111, permits this magazine to drop by gravity to the required position the same being subsequently raised out of operating position by a continued rotation of said cam.

As best illustrated in Figures 5 and 15 these magazines or work-storing receptacles, are provided with narrow necks 103 at their lower ends in which the work lays in superimposed relation and as the magazines are 50 dropped into operative position the vertically-sliding latches 104, which limit the endways motion of the work in these necks, engage the bearings 105 at one end and the supporting center 51 at the other end, see 55 Figures 5, 15 and 16, to raise them out of the way and permit the mandrels to be passed through the tubes and locked in working position therein, after which the magazines are raised through action of the levers 109, 60 110, 111 and cam 102, thereby causing the spring-pressed tube-retaining latches 112 to be forced open leaving the tube which is locked by the mandrels and as the magazine continues to rise, the latches 112 quickly

close again to prevent other tubes from 65 falling out.

After the fresh work has been positioned and the magazines removed the carriage may be again set in motion, which operation is performed in its regular order by causing 70 the cam 106 on disk 107 to act upon the pivoted lever arms 108 to force back the bar 90 from engagement with latch 92 to release the lever 93, the cam 97 now acting through the lever 98 throws in the clutch 94 to again 75 drive the carriage with its reciprocating motion. This inward movement of the clutch 94 swings the arm 93 to reposition the rock latch 92 and in so doing its notched end 92^a engages the end 93^a of the lever 92, see 80 Figure 2, securely locking this lever against a rocking action and so positively preventing the disengagement of the clutch 94 from the driving mechanism until this member 92 has been again operated at the finish 85 of the next piece of work.

As it is found in practice desirable to raise the tool from the work at the end of its forward stroke so as not to drag over the work, as the carriage returns for another stroke, I have provided an adjustable screw 113 on the side of the carriage so that as the carriage advances with the work, to the end of a cutting stroke, the end of this screw engages the arm 114 and throws it 90 backward causing its roll 115 to mount the inclined surface 116 on the bar 117 thus lifting the tool clear of the work, and at the last end of the return stroke of the carriage, the head of the screw 118 engages this lever 114 swinging it forward from contact with the member 117 permitting the tool to again drop into engagement with the work. Also on this lever arm 114 I have 95 mounted a laterally-extending arm 119 having a rearwardly-extending projecting cam-shaped end 120 which, when the lever arm is swung back on its pivot 121, causes said rearwardly turned end to engage the pin 122 drawing the tool-head to the left and withdrawing the stylus, presently described, from its pattern bar which is designed to produce lateral vibrations of the tool on the work. 100

In order to produce a broken or disconnected line along the surface of the work, I have provided a pattern bar 123, the surface of which may be scalloped, as illustrated in Figure 21, which surface is designed to be engaged by the stylus 124, carried by the tool-head 68, so as to raise the tools intermittently during the length of a working stroke. The shape of the scallops of this bar may be, of course, varied to produce different designs upon the work. 105

In order to move this bar as desired into operating position I have mounted a cam 125 on shaft 126 to be rotated from the shaft 110

80 through the miter gears 127, which cam is caused to control the positioning of the pattern bar 123 through the bar 128 and this cam will thus perform two functions 5 first, it is caused to move the pattern bar longitudinally in its guides 129 and so cause the tool to be raised at different points in different lines through its longitudinal stroke, also the high points of the cam serve to 10 force the guide pins 130 down the incline 131, thereby depressing this pattern bar out of engagement with its stylus permitting a plain line to be made by the tool, the spring 140 returning this cam-bar to raised position 15 when again released by the cam. In other cases when it is found desirable to raise the cutting tools from the work during an entire longitudinal stroke, or some portion thereof, I have provided a plain-faced pattern bar 132, the working surface of which may be the entire length of the stroke or any portion thereof. This bar is supported on pins 133 in the inclined grooves 134 and is provided with an extension member 136 20 which engages a cam 137 also mounted on and rotated by the shaft 126 whereby this pattern bar 132 when pressed inwardly will be lifted into engagement with its corresponding stylus 138 to raise the tool-head 68 with its tools from the work, the spring 139 returning this bar to normal or dropped position when released by the cam.

In some cases such for instance as when it is desired to leave a plain surface on the work for a name plate or other similar purpose, I have mounted a raised member 141 on a collar 142 threaded on the shaft 80 whereby this raised portion may be adjusted longitudinally on the shaft or circularly 40 thereon, the same being adapted to be brought into position by the rotation of shaft 80 to be engaged by an individual stylus 142^a to form a plain space in any desired place on the surface of the work.

45 In addition to the provision of means for lifting the tools from the work as desired in order to produce different patterns thereon, I have also provided means for producing lateral vibrations or movements of the tools during their operation upon the surface of the work whereby a great variety of combination movements of the tool and consequently a great variety of designs upon the work may be produced; and the following is a detailed description of one means by which a great variety of such movements may be produced:—

As best illustrated in Figures 4, 5, 23, 24, and 25, I have mounted a cylindrical member 145 on a shaft 146 to rotate in bearings 147 movably mounted in ways 149 on the outside edge of the carriage 31, and on the face of this cylinder I may form any desired patterns in any suitable way to be 50 reproduced upon the work by lateral move-

ments or vibrations of the tools, but I preferably provide a plurality of longitudinally-disposed grooves in the face of this cylinder and in these grooves I mount bars 148 the outer edges of which may be scalloped or otherwise shaped to produce the desired lateral vibrations on the tool through the stylus 150 mounted on the tool-head 68.

In order to present the different pattern bars which are located about the surface 75 of this cylinder, to the stylus, I have provided a cam 151 to be moved with the carriage the same being mounted on the shaft 152 to be rotated step-by-step at the end of each working stroke of the carriage by 80 means of the screw 153 acting against the lever 154, which lever in turn acts upon the spring-pressed oscillatory plate 155 on which the pawl 157 is mounted to engage and rotate the ratchet 156 which is also mounted 85 on this shaft 152 and connected to the cam 151. The lower end of a vertically-disposed rack bar 158 is caused under tension of spring 161 to rest upon and follow the edge 90 of this cam 151 and the teeth 159 of this bar engage the teeth 160 on the cylinder shaft 146 and as the cam is rotated step-by-step a corresponding rotation is transmitted to the pattern cylinder 145. The working face of this cam may be so shaped as to 95 produce different degrees of movement of the rack-bar for the purpose of moving into position the desired pattern bar in the cylinder.

It will also be seen that this cylinder 100 operating mechanism is mounted upon the carriage to move with it while the adjustable screw 153 is supported in a relatively-fixed position from the base of the machine. This pattern cylinder is positively held 105 in any of its several working positions by means of a spring-pressed pawl 162 which engages notches 163 in the edge of the ratchet wheel fixed to the cylinder shaft 146, which pawl is withdrawn from its notch by engagement at its lower end 164 with the relatively-fixed cam 165, see Figures 23 and 25, which cam is mounted on the base 30 of the machine, so as to permit a free or unrestricted movement of the cylinder through 110 the cam-operated mechanism above described.

In order to provide a greater variety of designs upon the work it is found of advantage to adjust the cylinder 145 with its patterns endwise relative to its operating stylus 150 whereby the position of each succeeding figure produced on the work may be varied. To accomplish this longitudinal positioning of the pattern roll I have rotatably mounted on the carriage a horizontally-disposed cam 166 on the stud 167 in position to engage the end of the contact pin 168 projecting from the end of the cylinder support 147.

A step-by-step rotating motion is imparted to this cam by the bringing up of the oscillatory plate 169, which is mounted on the stud 167, against the screw 170 supported from the base 30. On this plate is mounted a spring-pressed pawl 171 which engages the ratchet teeth 172 which ratchet is connected to the cam 166 whereby at the end of each working stroke the ratchet is caused to rotate the cam and through the contact pin 168 move the pattern cylinder into the desired position longitudinally relative to its stylus 150.

By the use of my improved engraving machine I am enabled to produce any desired form of ornamentation which may be produced by a combination of lateral and longitudinal movements of the tool upon the work.

I have shown and described a rotating cylinder for carrying different patterns to produce different lateral vibrations of the tool upon the work but I do not wish to be restricted to this particular arrangement of pattern carrying devices as these lateral movement controlling patterns may be in any suitable form and carried and operated by any desired or suitable means.

By the use of my improved engraving machine I am enabled to mount any desired number of pieces of work upon a reciprocating carriage and to simultaneously operate upon all of said pieces, and simultaneously release said pieces and replace them by fresh pieces when finished and means are provided for automatically shifting the pattern producing members to produce different designs upon the work by both lifting the tool from the work during the longitudinal operation of the same and also by producing a wide variety of lateral vibrations to the tool or tools during its longitudinal working stroke.

I have shown and described one form of mechanism for engraving different patterns upon the surface of the work, but I do not wish to be restricted to the particular mechanism herein shown and described as I reserve the privilege of resorting to all the mechanical changes to which the device is susceptible, the invention being defined and limited only by the terms of the appended claims.

I claim:

1. In an engraving machine, a work-support, an engraving tool, means for producing a relative longitudinal movement of the tool and work during the tool operating periods, and means for automatically discharging finished work from said support and positioning fresh work therein.

2. In an engraving machine, a work-support, an engraving tool, means for producing a relative longitudinal movement of the tool and work during the cutting period,

means for arresting the action of the tool upon the work after finishing the work, and means for automatically discharging the finished work from said support and positioning fresh work therein.

3. In an engraving machine, a carriage, means for supporting work on said carriage, a tool, means for moving said work and tool relatively, means for automatically withdrawing said support from the work when finished and positioning fresh work thereon.

4. In an engraving machine, a movable work-supporting carriage, means for rotatably supporting work on said carriage, a relatively fixed tool, means for automatically discharging the work from said support when finished and positioning fresh work thereon.

5. In an engraving machine, a carriage, means for rotatably supporting work on said carriage, an engraving tool, means for moving the carriage with its work relative to said tool, a work-supporting magazine above the carriage, means for automatically discharging the work from its support on the carriage when finished and positioning fresh work on the carriage from said magazine.

6. In an engraving machine, a carriage, means for supporting a plurality of separate pieces of work on said carriage, a tool for operating upon each piece of work, a work-supplying magazine for each support, and means for automatically discharging all of said pieces of work simultaneously from said support when finished and positioning fresh pieces of work from said magazines to each of said supports.

7. In an engraving machine, a carriage, means for supporting a plurality of separate pieces of work on said carriage, a tool for operating upon each piece of work, and means for automatically removing all of said pieces of work simultaneously from their supports when finished.

8. In an engraving machine of the planer type, a carriage, a plurality of work-supporting mandrels on said carriage, a relatively fixed engraving tool mounted to operate upon each piece of work carried by said mandrels, means for automatically withdrawing the mandrels from the work when finished, means for automatically positioning fresh work and repositioning said mandrels in said work, and means for causing the tools to again operate upon the work and repeat said cycle of operations.

9. In an engraving machine, a carriage, means for supporting work on the carriage, a tool, means for moving the work relative to the tool, means for arresting the action of the tool upon the work when finished, means for automatically discharging the work from said support when finished and

- positioning fresh work thereon, and means for again setting in motion the carriage with its work to subsequently repeat the said cycle of operations.
5. 10. In an engraving machine, a work-support, an engraving tool, means for producing a relative working movement of the tool and work, a magazine, means for automatically arresting the action of the tool 10 upon the work when the latter is finished, removing the finished work from its support, and replacing it with fresh work from said magazine, and means for again causing the tool to resume its action upon the 15 work.
11. In an engraving machine, a work-support, an engraving tool, means for producing a relative working movement of the tool and work, means for ejecting the finished 20 work, a magazine for carrying a supply of work, means for moving the magazine to present the work to said support, and means for replacing the discharged work with finished work from said magazine.
25. 12. In an engraving machine, a work-support, an engraving tool, means for producing a relative longitudinal working movement of the work and tool, means for producing a relative lateral movement of the 30 work and tool, and means for automatically discharging the work when finished from said support and positioning fresh work therein.
35. 13. In an engraving machine, a carriage, means for supporting the work on the carriage, a tool, means for moving the work longitudinally relative to the tool, means for moving the tool laterally relative to the work, and means for automatically replacing 40 the work when finished with fresh work.
45. 14. In an engraving machine, a carriage, means for supporting the work upon the carriage, a tool, means for moving the work longitudinally relative to the tool, a pattern member for simultaneously producing a lateral vibration of the tool while acting upon the work, and means for automatically discharging the work when finished and replacing it with fresh work.
50. 15. In an engraving machine, a tool mounted in a head, a laterally yieldable resilient support for said head, a longitudinally movable carriage for supporting the work, and means for imparting a lateral vibratory motion to said head while the tool carried thereby is moving longitudinally along the work.
55. 16. In an engraving machine, a head for supporting the working tool, a pair of resilient arms for supporting said head, a longitudinally movable carriage on which the work is mounted, and means for effecting a lateral vibration of said head while the tool is in operation with the work.
60. 17. In an engraving machine, a tool, a carriage, work rotatably mounted on said carriage, means including a clutch for reciprocating said carriage, means for throwing out said clutch to stop the carriage at a predetermined point in the rotation of the work, means for automatically throwing in the clutch, and means for locking the clutch when in its in or engaging position.
65. 18. In an engraving machine, a tool, a carriage, work rotatably mounted on said carriage, means including a clutch for reciprocating said carriage, means for throwing out said clutch to stop the carriage at a predetermined point in the rotation of the work, means for automatically discharging the finished work and repositioning fresh work in said carriage, and means for automatically repositioning the clutch to start the carriage when fresh work has been positioned.
70. 19. In an engraving machine, a tool, a carriage, means for imparting a step-by-step rotation to the work on said carriage, means including a clutch for reciprocating said carriage, means for throwing out said clutch to stop the carriage at a predetermined point in the rotation of the work, means for automatically replacing the finished work with fresh work, means for throwing in the clutch to start the carriage, and means for locking said clutch in engaged position.
75. 20. In an engraving machine, a tool, a carriage, means for mounting a plurality of pieces of work on said carriage, means for simultaneously imparting a step-by-step rotation to said pieces of work, means for reciprocating said carriage relative to said tool, means for throwing out said clutch to stop the carriage at a predetermined point in the rotation of the work, and means for automatically and simultaneously replacing all of said pieces of work when finished with fresh work.
80. 21. In an engraving machine, a work-support, an engraving tool, means for producing a relative longitudinal working movement of the tool and work, a series of cooperating patterns for also imparting a lateral vibration to said tool, and means for automatically positioning said members.
85. 22. In an engraving machine of the planer type, a work-support, an engraving tool, means for producing a relative working longitudinal movement of said tool and work, a plurality of different patterns, and means for automatically positioning said patterns to impart different lateral vibrations to the tool while acting upon the work.
90. 23. In an engraving machine of the planer type, a work-support, an engraving tool, means for producing a relative longitudinal working movement of said tool and work, a roll carrying a plurality of spaced apart patterns, means for automatically rotating

- said roll to selectively position the pattern required, and means for engaging said members to impart the desired lateral vibration to the tool while operating upon the work.
24. In an engraving machine, a work-support, an engraving tool, means for producing a relative longitudinal working movement of said tool and work, and patterns for producing both a vertical and a lateral movement to the tool during its action upon the face of the work.
25. In an engraving machine, a work-support, an engraving tool, means for producing a relative longitudinal movement of said tool and work, and independently operable pattern members for producing both a vertical and a lateral working movement to the tool during its action upon face of the work.
26. In an engraving machine, a work-support, an engraving tool, means for moving the work longitudinally relative to the tool, a plurality of pattern members for producing lateral vibrations of the tool upon the work, and a cam for presenting different patterns to produce different vibrating effects upon the tool.
27. In an engraving machine, a work-support, an engraving tool, means for producing a longitudinal movement of the work relative to the tool, independently operable pattern members for producing both a vertical and a lateral working movement to the tool during its movement along the face of the work, and cams for controlling the positioning of said pattern members.
28. In an engraving machine, a work-support, an engraving tool, means for producing a relative longitudinal working movement of said tool and work, a series of pattern bars for obtaining a lateral movement of the tool relative to the work, and independent means for producing a vertical movement of the tool during its movement across the face of the work.
29. In an engraving machine, a work-support, an engraving tool, means for producing a relative longitudinal movement of said tool and work, a series of pattern bars for obtaining a lateral movement of the tool relative to the work, independent means for producing a vertical movement of the tool during its movement across the face of the work whereby different figures may be produced at intervals along the length of the work, and means for automatically varying the longitudinal position of the bar to vary the relative position of the figures.
30. In an engraving machine, a work-support, an engraving tool, means for producing a relative longitudinal movement of said tool and work, a pattern bar for imparting a relative vibration to said tool while operating upon the face of the work, means for producing a relative lateral movement of the tool and work, and means for producing an endways movement of said bar to change the relative positions of the pattern on the face of the work.
31. In an engraving machine, a work-support, an engraving tool, means for producing a relative longitudinal movement of said tool and work, and cam-actuated means for automatically raising the tool from the work at predetermined intervals.
32. In an engraving machine, a work-support, an engraving tool, means for producing a relative longitudinal movement of said tool and work, and a longitudinally-disposed cam-actuated bar for automatically raising the tool from the work at predetermined intervals.
33. In an engraving machine, a work-support, an engraving tool, means for producing a relative longitudinal movement of the tool and work, a pattern bar, and a cam for positioning said bar at predetermined intervals during the movement of the tool over the face of the work to control the action of the tool upon the work.
34. In an engraving machine, a work-support, an engraving tool, means for producing a relative longitudinal movement of said tool and work, a pattern bar for causing the tool to engage the work intermittently during a working stroke, and a cam for positioning said bar at predetermined intervals during the production of the pattern upon the face of the work.
35. In an engraving machine, a head for supporting a plurality of working tools, means for imparting a lateral movement to said head, cooperating compensating levers for yieldably supporting the tools in said head, and a longitudinally reciprocating carriage for presenting the work to the tools.
36. In an engraving machine, a tool head, a plurality of tools mounted in said head, a laterally yieldable flexible support for said head, cooperating compensating rocking levers for yieldably supporting the tools in said head, a longitudinally movable carriage for presenting the work to said head while the tools are operating upon the work.

In testimony whereof I affix my signature.

CHARLES H. FIELD.
